PORTABLE ESCALATOR

Floyd Coryell, Los Angeles, Calif.
(6871 Franklin Ave., Hollywood, Calif.)
Filed June 1, 1959, Ser. No. 817,309
10 Claims. (Cl. 198—16)

This invention relates to an escalator and more particularly to a portable escalator of the type set forth in an application for United States Letters Patent Serial No. 689,205 filed by me October 9, 1957, now U.S. Patent No. 2,929,482, of which this application is a continuation-in-part.

The invention has for its primary object the provision of a power driven escalator which may be moved from place to place and adjusted to various heights.

A particular object is to provide an escalator which is adapted for use in an airport as a means for facilitating the loading and unloading of passengers and crew of aircraft.

Another object is to provide an escalator wherein the flight of steps thereof may be disposed at various inclinations and whereby the upper end of the escalator may be raised and lowered to accommodate it to door sills of various levels.

Another object is to provide an escalator wherein the runs of endless conveyors on which steps are mounted may be maintained taut and also wherein the treads of the steps will be maintained at least substantially horizontal irrespective of various working inclinations of the escalator.

With the foregoing objects in view together with such other objects as may subsequently appear, a preferred embodiment of the invention is illustrated in the accompanying drawings in which:

FIG. 1 is a perspective view of the escalator;

FIG. 2 is a view in front elevation partly in section and with portions broken away;

FIG. 3 is a plan view of the front end portion of the escalator as seen on the line 3—3 of FIG. 2;

FIG. 4 is a detail in section and elevation taken on the line 4—4 of FIG. 2 as seen in the direction indicated by the arrows;

FIG. 5 is a view in side elevation of the escalator with the hand rail portion and other parts removed;

FIG. 6 is a view in section and elevation as seen on the line 6—6 of FIG. 2 with portions broken away;

FIG. 7 is a detail in cross section as seen on the line 7—7 of FIG. 6 in the direction of the arrows;

FIG. 8 is a perspective view of a step of the escalator;

FIG. 9 is an enlarged detail in section of the lower end portion of the escalator as seen on the line 9—9 of FIG. 2, with portions removed;

FIG. 10 is a view in elevation of the rear end of the escalator with parts broken away and parts removed;

FIG. 11 is a view in section and elevation taken on the line 11—11 of FIG. 10 with parts removed;

FIG. 12 is a view in section and elevation as seen on the line 12—12 of FIG. 2 in the direction of the arrows;

FIG. 13 is an enlarged cross section of the lower end housing taken on the line 13—13 of FIG. 5 as seen in the direction of the arrows, portions being removed;

FIG. 14 is an isometric view of a conveyor guiding element shown in cross section in FIG. 13;

FIG. 15 is a detail in section and plan as seen on the line 15—15 of FIG. 5; and

FIG. 16 is a view in section of the escalator housing taken on the line 16—16 of FIG. 1, operating mechanism being removed.

Referring to the drawings more specifically A indicates the escalator bed which is mounted on wheels B for

2

movement over a supporting surface, and C denotes generally an escalator which as particularly shown in part in FIG. 5 embodies a lower end housing D fixed on the bed A and an upper end housing E connected to the housing D by three superimposed spaced pairs of spaced parallel inclined links comprising an upper pair of links F, an intermediate pair of links G and a lower pair of links H. The pairs of links F—G are pivotally connected at their lower end to the upper inner portion of the lower housing D by hinges a and at their upper ends to the upper portion of the upper housing D by hinges b; while the lower pair of links H are pivotally connected at their lower end by hinges c to the lower portion of the inner end of a conveyor guiding element J mounted in the lower housing D, and have their upper ends connected by hinges d to the lower portion of the upper housing E.

The links F—G—H have open ended longitudinal channels e on their inner sides extending throughout the lengths thereof. The channels e of the intermediate pair of links G constitute guideways for the upper run of an endless conveyor K as shown in FIG. 6; the channels e of the upper pair of links F constitute guideways and supports for the ends of steps L carried on the conveyor K; and the channels e of the lower pair of links G serve as guideways for the lower run of the conveyor and also for the ends of steps L mounted on the conveyor.

The conveyor K comprises a pair of spaced parallel endless sprocket chains the return portions of which pass around pairs of sprocket wheels 20—21 located respectively in the lower and upper housings D—E; the pair of sprocket wheels 20 being idlers revolubly mounted on a shaft 22 supported in the housing D for movement longitudinally thereof, and the pair of sprockets 21 being drivers fixed on a drive shaft 23 journaled in bearings mounted in the upper housing E. The shaft 22 is fitted adjacent its ends with rollers 24 which are supported in horizontal runways 25 in the side walls of the housing D where the shaft 22 is moveable transversely back and forth in the direction of the runs of the sprocket chains to maintain the runs of the chains taut as will be later described. The drive shaft 23 is journaled in bearings in the housing E and has an end thereof geared to a reversible electric motor M carried by the housing E.

The steps L, particularly shown in FIG. 8, embody a rectangular flat tread f and an integral downwardly and inwardly curved front apron g, and mounted on the opposite ends of the steps at the juncture of the tread and apron are rollers h which are adapted to traverse the channels e of the upper and lower pairs of links F and H; the parallel inner margins of the links of each of such pairs being spaced apart to extend contiguous but in spaced relation to the ends of the steps. Projecting from the ends of the step treads, adjacent the inner margins thereof, are trunnions i the outer ends of which are pivotally engaged with the sprocket chains of the conveyor K, whereby the steps L are carried on the conveyor. The steps L are connected to the conveyor in such spaced relation to each other that the aprons g thereon will extend proximate the inner margins of the steps as shown in FIG. 6. The aprons g are curved inward from the treads f so that when their outer margins are disposed proximate the rear margins of an adjacent step the forward edges of the treads of the so related steps will overhang the treads therebelow, as shown in FIG. 6. The upper and intermediate links F and G are arranged in laterally offset and vertically spaced relation to each other as shown in FIG. 7 so that the treads f of the steps traversing the links F and G will be disposed horizontally or nearly so in angular relation to the runs of the conveyor, and in order that the treads of the several steps may be disposed in alignment with each other and with the lower runs of the conveyor trav-

ersing the lower links H, the latter are formed of a width to underlie the laterally offset links F and G in vertical alignment therewith, with the channels e in the links H of a depth to receive the rollers h on the steps, the conveyor chains and the trunnions i, as shown in FIG. 7.

In order that the rollers h on the steps L may be brought into lateral alignment with the runs of the conveyor chains as the steps approach, pass around and leave the sprocket wheels 20-21, the housings D and E are equipped respectively with guideways 26 and 27 which lead from the ends of the channels e in the upper and intermediate links F and G around the sprocket wheels 20-21 to the ends of the channels e in the lowermost links H.

Means are provided for supporting and raising and lowering the upper end of the escalator which means constitutes an electrically operated elevator applied to the upper housing E and here shown as comprising a pair of screw jacks N-O mounted on the bed A. Each of the jacks N-O embodies a vertically disposed threaded shaft 28 mounted on and extending through a tubular standard 29 rigidly affixed on the bed A; an internally threaded beveled gear wheel 30 being screwed on the shaft 28 and supported in a yoke 31 affixed to the upper end of the standard 29 whereby the gear wheel is held against movement longitudinally of the shaft on rotation thereof, but on being rotated will advance or retract the shaft 28. The gear wheels 30 are collectively and uniformly driven from a single power source comprising an electric motor P mounted on the bed A having a driving sprocket wheel 32 on its drive shaft which wheel engages a sprocket chain 33 passed around sprocket wheels 34-34 on stud shafts 35-35 journaled in the yokes 31 and having beveled pinions 36 thereon engaged with the gear wheels 30 indicated in FIG. 15. The housing E is provided with a pair of longitudinally extending parallel rails 37-37 which bear on rollers 38-38 on the upper ends of the shafts 28-28 whereby the housing E may move horizontally relative to the shafts 28-28 as the latter are moved vertically.

The conveyor guiding element J in the lower housing particularly shown in FIG. 14, is supported at its outer end on and connected to the shaft 22, it having slots 40 in its outer end portion to accommodate the idler sprocket wheels 20-20, as shown in FIGS. 13 and 14. Rollers 41-41 on the forward end portion of the element J revolvably bear on tracks 42-42 in the housing E whereby the element J is supported for longitudinal movement relative to the housing E. The element J is composed of a lower section 43 and an upper section 44 for positioning beneath and above the shaft 22 in engagement therewith and has spaced apart side portions m and n to afford passage therebetween of the escalator steps; the side portions m and n being connected together by a bottom wall Q. The guiding element J has horizontal top and bottom walls r-s which serve as guides for horizontal lengths of the upper and lower runs of the conveyor chains leading between the sprocket wheels 20-20 and the lower ends of the links F-G and H.

Means are provided for shifting the shaft 22 laterally to maintain the runs of the conveyor K taut and compensate for variation in the length of such runs due to raising or lowering of the upper end of the escalator; which means is controlled by variation of the inclination of the lower link H the lower end of which connects with the element J as before described. The aforesaid actuating means comprises a pair of arms 43-43 pivoted to swing vertically on pivots 44-44 mounted on the upper inner end of the housing E, the arms 43-43 leading downward at an inclination and having their lower free ends engaged by pin and slot connections 45 with the lower links H at points spaced from their hinged lower ends. Connected to the arms 43-43 by pivots 46 are arms 47 leading to and connecting with the end portions of the shaft 22 whereby rocking of the arms 43-43 will advance or retract the shaft 20. This movement of shaft 20 effects

5 a corresponding movement of the element J so as to impart longitudinal movement of the lower link H and thereby permit the link H to assume various angular relations to the parallel links F and G and thus prevent binding of the links.

10 The escalator embodies a conventional type of traveling hand rails R-R including a pair of hand belts 48-48 mounted on a pair of endless sprocket chains 49-49 which are spaced above the sprocket chains 49-49 which are spaced above the sprocket chains of the conveyor K. The return bends at the lower ends of the chains 49-49 pass around and are engaged by a pair of idler sprocket wheels 50-50 arranged in housings U-U erected on the housing D, as shown in FIG. 12. The upper end 15 portions of the chains 49-49 pass over direction rollers 52-53 carried on the side walls 54-54' of housings V-V fixed to the upper links F-F as shown in FIG. 16, and extend horizontally in fixed housings W-W on the upper housing E with the upper return bends of the 20 sprocket chains 49-49 passing around driven sprocket wheels 55-55 fixed on shafts 56-56 which are driven by chain gearings S-S from the motor driven shaft 23 as shown in FIG. 11. The direction rollers 53 are mounted on spring pressed stud shafts and act to take up slack 25 in the hand rail chains 49-49.

As shown in FIG. 16, the inner side walls 54-54 of the portions V-V of the hand rail housings are erected from the links F-F, while the outer side walls 54' are mounted on brackets or gussets y carried on the links 30 F-F and inner side walls 54; the outer side walls 54' being extended below the links F-F to overlie the outer sides of the links G-G and H-H proximate and in slideable relation thereto. The ends of the housings V extending above the links F-F are adapted to slidably extend into the contiguous ends of the end housing U-U and W-W thereby permitting swinging of the portions V-V relative the end portions U-U and W-W on raising and lowering the escalator.

35 The housing D has a top wall constituting a platform u which has a rectangular opening v therein leading from the inner margin of the housing in which several of the steps L align between the sprocket wheels 20 and the lower end of the links F-G and on which persons stand in either approaching or leaving the escalator, stairs T being provided on the rear end of the escalator bed to give access to the platform u on boarding the escalator or to give egress therefrom on leaving the escalator. The upper housing E has a top wall constituting a platform w which has a rectangular opening x leading from its inner edge 50 in which several of the steps align between the upper ends of the links F-G and the sprocket wheels 21 on which persons stand on either leaving or approaching the escalator.

55 In the operation of the invention the escalator is wheeled to a desired location and, if need be, the upper end housing E is raised or lowered by the elevators N-O to bring the platform w on the housing E to a desired level relative to an elevated landing, such as the sill of an aircraft door. The threaded shafts of the elevator 28 60 serve to retain the upper end of the escalator in any adjusted position.

On setting the motor M in operation in either direction, the conveyor K will be driven accordingly to advance the steps L which in traversing the inclined links F and G will be disposed with their treads f extended horizontally, and when fed by the guideways 25-27 in the housings D-E into the lower links H, the adjacent treads will be aligned with each other and will be supported with the lower runs of the conveyor chains in the channels e of the links H. The steps L will then be inverted and the aprons g thereof will project upwardly from between the links H into the space between the links H and G as shown in FIG. 6. The hand rails R-R will be moved in unison with the conveyor K.

In raising and lowering the housing E the links F and

G will swing in parallel relation to each other with the platform w of the housing maintained in a horizontal position. In order to permit this movement with the third links H the latter must be capable of longitudinal movement relative to the links F—G. This movement is afforded by connecting the lower ends of the links to the moveable element J in the lower housing D so that the links H may move forward when the housing E is moved upward and will move backward when the housing is lowered thus preventing binding as would otherwise occur.

Exposed portions of the escalator operating mechanism may be housed in any suitable fashion such as indicated in FIG. 1.

While I have shown and described a specific embodiment of the invention, I do not limit myself to the exact details of construction set forth and the invention embraces such changes, modifications and equivalents of the parts and their formation and arrangement as come within the purview of the appended claims.

I claim:

1. In an escalator embodying an upper pair of parallel links, an intermediate pair of parallel links, and a lower pair of parallel links; each of said links having open ended channels extending throughout the lengths thereof, means pivotally supporting said links at one end thereof for vertical swinging movement collectively into various inclined positions, a housing to which the other ends of said links are hinged, means for raising and lowering said housing, an endless conveyor having runs arranged in the channels in said intermediate and lower links, a series of steps mounted on said conveyor, means supporting outer portions of said steps in said upper pair of links, and means for driving said conveyor.

2. The structure called for in claim 1 in which the means to which said lower links are pivoted is moveable longitudinally of said conveyor.

3. In an escalator embodying lower and upper end housings, spaced superimposed pairs of spaced parallel links hingedly connected at their ends relative to said housings comprising an upper pair, an intermediate pair, and a lower pair; said links having open ended channels on their inner sides extending throughout the lengths thereof, endless conveyors having runs within the channels of the intermediate and lower pairs of links, pairs of sprocket wheels in said housing engaging the end portions of said conveyor, means for driving one pair of said sprocket wheels, a series of steps pivotally connected to the runs of said conveyor, rollers on the ends of said steps, and guideways in said housing opening to the ends of the channels in the upper and lower pairs of links; said rollers being arranged to traverse said guideways and the channels in said upper and lower links.

4. The structure called for in claim 3 together with means for raising and lowering said upper end housing adapted to hold said housing at various levels.

5. The structure called for in claim 3 together with means controlled by said lower pair of links as they are moved by raising or lowering said upper housing for shifting the sprocket wheels in said lower end housing laterally to maintain the conveyor taut.

6. The structure called for in claim 3 in which said guideways in said housing direct end portions of said conveyor horizontally between the ends of said links and said sprocket wheels.

7. In an escalator, a wheeled bed, a housing mounted on said bed, a plurality of pairs of links hinged relative to said housing for vertical swinging movement, a housing to which the outer ends of said links are hingedly connected, an endless conveyor supported by said housings and links, steps mounted on said conveyor, and means for driving said conveyor, an elevator comprising a pair of vertically extending threaded shafts, rollers on the upper ends of said shafts, rails on said second housing seating on said rollers and means on said bed engageable with said shafts to effect vertical movement thereof and of said second housing.

8. In an escalator, a bed, an end housing fixed on said bed having a top wall and side walls, a shaft mounted on said side walls for lateral movement, a pair of sprockets on said shaft, a guiding element connected to said shaft projecting forwardly therefrom within said housing, having a forward end portion spaced below said top wall, a pair of channeled links hinged to said forward end portion of said element, a second end housing having a top wall and a lower portion, said links having outer ends hinged to the lower portion of said second housing, a second pair of channeled links having their ends hinged to the top walls of said housings, endless sprocket chains passing around said sprocket wheels and having runs leading through said pairs of channeled links into said second housing, sprockets in said second housing engaging said chains, means for driving said sprockets; a series of escalator steps pivoted on said chains, rollers on the ends of said steps, a third pair of channeled links having their ends hinged to the top walls of said housings with the links spaced upwardly from said second pair of links; guide means in each of said housings including the guiding element aforesaid for directing the rollers on said steps as the latter advance with said chains around said sprocket wheels and into said first and last named pairs of channeled links, and means for raising and lowering said second housing relative to said bed.

9. The structure called for in claim 8 together with a hand rail housing embodying sections mounted on said end housings and an intermediate section mounted on said last named pair of links.

10. A portable moving stairway having an endless chain of motor driven steps and comprising a mobile frame support, upper and lower platform means, means operative to adjust the inclination of the stairway, each of the steps having support means at each side, inclined elongated guide means at each side of the steps engaged by the support means and pivotally mounted relative to the platform means such that the upper tread of the steps remains horizontal with variation of the inclination of the stairway, and elongated guide means at the upper and lower platform means forming continuations of the inclined guide means.
